UNITED STATES PATENT OFFICE.

IVAN TURNER, OF LONDON, ENGLAND.

ROTARY ENGINE AND THE LIKE.

Application filed July 14, 1925, Serial No. 43,539, and in Great Britain December 23, 1924.

This invention relates to rotary engines, pumps, compressors and the like, of the type in which a cylindrical rotor is mounted in a non-circular cylindrical casing, and the rotor is furnished with a number of radially sliding vanes or blades, the outer ends of the blades having suitable packing means making contact with the interior of the casing and the inner ends of the blades being connected by means of links which are hinged together in series. In such machines having four blades arranged at right angles to one another, the links constitute a parallelogram; the present invention is applicable to machines having four sliding blades or any greater number, the links forming a closed figure with a corresponding number of sides.

The invention has for its principal objects to control the radial motion of the vanes so as to reduce friction and prevent excessive contact pressure due to centrifugal force, and to allow for variations in the radial motion.

According to this invention the radial reciprocation of the link-connected blades is controlled by one or more stationary cams co-operating with rollers mounted at the inner ends of the blades, preferably coaxially with the hinge between the blade-connecting links. The shape of the cam is such as to produce the required inward and outward movements of the respective blades in conformity with the working of the link motion and the internal shape of the casing.

Contact may be maintained between the cam surface and the rollers by the use of springs or spring-loaded links connecting the inner ends of the blades, the springs being used simply for the purpose of taking up the mechanical clearances in the linkwork.

The invention is hereafter described with reference to the accompanying drawing, in which:—

Figure 1 is a longitudinal section of a rotary steam engine according to the present invention, having four sliding blades connected by links which form a parallelogram.

Figure 2 is an end view of the same, half in section, half in elevation.

Figures 3 and 4 are two views at right angles of a modified form of hinge joint for the links.

Figure 5 is a diagrammatic end view of an alternative form of engine having eight

blades sliding radially in the rotor or piston body.

Figure 6 is a part sectional elevation, corresponding to the right side of Figure 2, of one of the rotary inlet valves and its actuating means.

Figure 7 is a cross section through one of the exhaust valves, and

Figure 8 illustrates the preferred arrangement of steam distributor for operating the exhaust valves.

As illustrated in Figures 1 and 2, the casing of the engine is constructed in a number of parts to facilitate assembly, the central part *a* being of oval cylindrical shape to form the working chambers, and the outer parts or end covers *a'* being fitted with the necessary valves for the working fluid and suitable bearings for the shaft of the rotor *b*; the rotor is built up with end-rings *b'*, of which one is secured to its shaft by a dished flange-connection *b''*. The blades *c* mounted in the rotor so as to be slidable radially in slots therein, are provided at their outer ends with suitable means for packing the joints between the relatively moving parts; the inner ends of the blades carry lugs or eyes *d*, the interior of the rotor being recessed as at *e* to accommodate these lugs when the blades are in the outer position.

The links *f* of the parallelogram connecting the blades together in the known manner, are hinged to the blades *c* by means of pins *g* fitted through the lugs *d*. The ends of the two links *f* engaging each pin *g* are of single and duplex construction respectively, for example diametrically opposite links may be duplicated as shown to centralize the pressure upon the hinge-pins.

On each side of the hinge connection, each pin *g* carries a roller *h* adapted to travel upon the exterior of a cam *i*; the two cams controlling the four pairs of rollers are mounted upon a central sleeve *j* secured to the cover-plate *a'* at one end of the casing and provided with suitable bearings for the rotor and its shaft. As seen in Figure 2, the cams *i* are of oval profile with two lobes or swells, substantially corresponding to the interior of the oval casing.

The working chambers *x* are provided with exhaust ports *v* at or towards each end, the port at one end of the chamber being opened for forward running and that at the

other end for reverse running. As each vane c moves inwards, it passes across the open port v , and allows the exhaust of the steam acting behind the vane.

In Figure 7, the exhaust port v is shown controlled by a valve a^3 having a piston v^1 operated by fluid pressure which can be directed to either set of valves, viz, for forward or for reverse running, by means of a distributor. The latter (see Figure 8) comprises a double poppet valve t actuated by a reversing lever u working over a quadrant u^1 , steam entering at boiler or steam chest pressure into the central chamber k of the distributor, so as to pass into one or other of the side chambers k^1 which communicate through pipes l with the respective pairs of exhaust port pistons v^1 ; according to the position of lever u either pair of pistons can be subjected to the steam pressure so as to close the corresponding exhaust ports v .

Each of the side chambers k^1 contains a relief valve such as a spring loaded ball k^2 , adapted to be lifted off its seat by the spindle t^1 of the poppet valve t , in order to release the pressure from the pipes l and pistons v^1 of the exhaust ports to be brought into operation, the pressure in the working chamber then forcing back the corresponding piston valves so as to leave these ports open to exhaust.

When changing over from one direction to the other, pressure is momentarily applied to all the pistons v^1 so as to maintain the two pairs of exhaust ports closed. During this time, while the lever u is in neutral position, the steam contained in the working chambers is thus trapped and becomes compressed by the momentum of the engine, which action assists the slowing of the engine for reversal and tends to start the motion in the opposite direction as required.

The inlet valves a^2 are of rotary type and driven by skew gearing m from a cross shaft n which operates two inlet valves at diametrically opposite points in the casing a , (see Figures 2 and 6), the cross shaft being itself driven from the main shaft o by another set of skew gears m^1 . Axial travel of the cross shaft can be produced by a screw mechanism p and hand wheel p^1 at one end of the shaft, by which the timing of the valves in relation to the rotor can be regulated or reversed.

The steam admitted through the rotary inlet valves a^2 which open at a suitable moment after the vanes c have passed the exhaust valves a^3 , passes along the spaces b^1 on the periphery of the rotor to the upper and lower chambers x seen in Figure 2, mingling with the fluid remaining in the lower chamber which (in the direction of rotation indicated) is at the end of its exhaust stroke, and providing a working charge for the blade in the upper chamber,

the admission to the latter being cut off at the desired point by the rotary inlet valve and the charge then expanded until the opening of the exhaust valve a^3 when the blade reaches the corresponding point.

Where it is desired to allow for slight variations in the radial movement of the blades as determined by the shape of the casing and the cams, spring links may be employed. As shown more particularly in Figures 3 and 4, the link is of telescopic construction, the opposite ends being slidable through a pair of cross bars k pressed apart by springs l which tend to shorten the link and thereby keep the rollers in contact. The extension of the link is limited by an adjustable stop m screwing through one of the cross bars k , in order to prevent the tips of the blades from coming into contact with the casing through centrifugal force in case of excessive speed.

Figure 5 illustrates another form of construction of the engine, in which the casing a , instead of being of oval shape, is formed with four chambers around the cylindrical rotor b . The latter carries eight sliding blades c , which are controlled through the rollers h by means of a stationary cam i having four peaks, corresponding to the shape of the casing a , this cam being mounted upon a sleeve j as in the previous construction.

The pins g of the sliding blades are connected together in series by hinged links f , preferably spring-loaded as above described.

It will be understood that the invention can be applied to rotary engines with other numbers of sliding blades, as well as to pumps, compressors and the like.

What I claim is:—

1. A rotary engine, comprising a cylindrical rotor, a non-circular casing, said rotor mounted for rotation in said casing, a plurality of vanes mounted in said rotor and adapted to slide radially thereof, a plurality of spring links connecting the inner ends of said vanes, said spring links including yielding members with springs controlling the relative yielding motion of said members, and a stationary cam controlling the radial motion of said vanes, said spring links restraining the radial motion of said vanes as they approach their outer limit.

2. A rotary engine, comprising a cylindrical rotor, a non-circular casing, said rotor mounted for rotation in said casing, a plurality of vanes mounted in said rotor and adapted to slide radially thereof, a plurality of links connecting the inner ends of said vanes, said links including telescopic members and springs tending to shorten the links, and a stationary cam controlling the radial motion of said vanes.

3. A rotary engine, comprising a cylindrical rotor, a non-circular casing, said rotor mounted for rotation in said casing, a plu-

rality of vanes mounted in said rotor and adapted to slide radially thereof, a plurality of links connecting the inner ends of said vanes, said links including telescopic members, cross members, springs pressing said cross members apart to shorten the links, and means for limiting the extension of the links, and a stationary cam controlling the radial motion of said vanes.

5 4. A rotary engine, comprising a cylindrical rotor, a non-circular casing, said rotor

mounted for rotation in said casing, a plurality of vanes mounted in said rotor and adapted to slide radially thereof, a plurality of links connecting the inner ends of said 15 vanes, a stationary cam controlling the motion of said vanes, and means for allowing for variations in the radial motion of said vanes determined by said links.

In testimony whereof I hereunto affix my 20
signature.

IVAN TURNER.
